UNITED STATES PATENT OFFICE.

JOSEPH BROICH AND ADOLPH EMIL GUSTAV LUEBKE, OF BROOKLYN, N. Y.

ELECTRIC CLOCK-WINDING ATTACHMENT.

SPECIFICATION forming part of Letters Patent No. 355,434, dated January 4, 1887.

Application filed September 3, 1886. Serial No. 212,575. (No model.)

To all whom it may concern:

Be it known that we, JOSEPH BROICH and ADOLPH EMIL GUSTAV LUEBKE, of Brooklyn, in the county of Kings and State of New York, have invented certain new and useful Improvements in Electric Clock-Winding Attachments, of which the following is a specification.

The object of our invention is to provide a new and improved electric attachment for winding clock-springs, which attachment is so constructed as to keep the clock-spring wound continuously.

The invention consists in the combination, with a clock, of an electric motor, gearing for transmitting motion to the spring, and mechanism for automatically closing the electric circuit once in each hour, all as will be fully described and set forth hereinafter, and finally to be pointed out in the claims.

In the accompanying drawings, Figure 1 is a longitudinal cross-sectional view of a clock provided with our improved electric attachment for winding the spring. Fig. 2 is a face view of the same.

Similar letters of reference indicate corresponding parts.

A represents an electric motor of any suitable construction, the revolving parts of which are mounted on the shaft A', having a pinion, B, engaging with a cog-wheel, C, upon the shaft C, carrying a pinion, C', engaging with the cog-wheel D, mounted loosely on the shaft E, said wheel D carrying the barrel F for the mainspring G, one end of which is secured to the barrel and the other end to the shaft, from which, by suitable mechanism, the hands are driven. An arm, H, is mounted loosely on the shaft E, and is provided with a quadrant-notch, J, into which a pin, I, projects from an arm, K, fixed on the end of the shaft E. The arm H has attached to its free end a cross-piece or wiper, L, which is insulated from said arm H, and is adapted to come in contact with two contact-closing springs, M, placed side by side and connected with the opposite line-wires, a and b, which are connected with the battery and with the electric motor in the usual manner. Said springs M and their connection with the wire a are fastened on a suitable insulating-piece, N. A

pin, O, projects from the face of the wheel D a sufficient distance to strike the arm H.

The operation is as follows: As the spring uncoils, the shaft H is revolved in the direction of the arrow a'; and the arm H is revolved with the said shaft E as the pin I strikes one end of the notch or offset or recess J in the arm H. At the end of a revolution the arm H comes in contact with two springs, M M, and closes the circuit, whereby the motor is operated. The wheel D is rotated in the direction of the arrow a', and the pin O on said wheel moves around with it until it is in the position shown in dotted lines in Fig. 2, when it strikes against the arm H and pushes the same in the direction shown in dotted lines in Fig. 2, whereby the wiper or cross-piece L is moved beyond the ends of the contact-springs, the circuit is broken, and the electric motor stopped. The spring, which was wound a slight distance by the revolutions of the wheel D, continues to uncoil, and carries the arm and the pin attached to it to the position shown in full lines in Fig. 2, when the circuit is again closed and the spring wound again, and so on. The quadrant-notch must be provided on the arm H to permit the pin O to move the arm H from the position shown in full lines in Fig. 2 into the position shown in dotted lines in Fig. 2. The spring can only uncoil a comparatively short distance, as it is rewound every hour, and thus a very regular and improved winding attachment can be provided, which can be applied to any clock, and requires no considerable change in the clock mechanism.

As the spring is wound at comparatively short intervals, a small spring may be used to great advantage.

The spring is connected with the barrel F on the wheel D, but may be connected directly with the wheel D.

Having thus described our invention, we claim as new and desire to secure by Letters Patent—

1. In an electric clock-winding attachment, the combination, with a wheel mounted loosely on the shaft connected with the mainspring, which mainspring is connected with said wheel, of an arm mounted loosely on said shaft and operated by a pin on said shaft, a pin on the wheel mounted loosely on the shaft, two cir-

cuit closing springs, with which the end of the arm can come in contact, and an electric motor and gearing for transmitting motion from the electric motor to the loose wheel on the 5 spring-shaft, substantially as set forth.

2. The combination, with clock-work mechanism, of an electric motor, gearing for transmitting motion from the electric motor to the spring-shaft, an arm on the spring-shaft, and 10 two circuit-closing springs over which the end of said arm can wipe, substantially as set forth.

3. The combination, with clock-work mechanism, of the wheel D, mounted loosely on the spring-shaft E, a spring-barrel, F, secured on 15 the spring-shaft, an arm, H, having a notch,

J, a pin, I, projecting from an arm, K, on the shaft E into said notch J, an insulated cross-piece or wiper on the arm H, contact-springs connected with the line-wires, and an electric motor, and gearing for transmitting motion 20 from the electric motor to the wheel D, substantially as shown and described.

In testimony that we claim the foregoing as our invention we have signed our names in presence of two subscribing witnesses.

JOSEPH BROICH.

ADOLPH EMIL GUSTAV LUEBKE.
